UNITED STATES PATENT OFFICE.

FLORENCE GARRIGUE, OF DANVERS, MASSACHUSETTS.

TOY.

1,337,354.

Specification of Letters Patent. Patented Apr. 20, 1920.

Application filed August 11, 1919. Serial No. 316,557.

To all whom it may concern:

Be it known that I, FLORENCE GARRIGUE, a citizen of the United States, and resident of Danvers, county of Essex, State of Massachusetts, have invented an Improvement 5 in Toys, of which the following description, in connection with the accompanying drawing, is a specification, like characters on the drawing representing like parts.

10 This invention relates to improvements in toys and the object thereof is to provide a toy having eyes presenting a luminous appearance. More specifically the object of the invention is to provide a toy in the form 15 of a living being having eyes comprising a luminescent material which will enable said eyes to be visible in the dark so that the toy may be given to children with the assurance that it will "watch over" them during their 20 sleep.

I am aware that heretofore the faces of advertising devices, automatons and the like have been provided with eyes illuminated by incandescent lamps but such forms of illuminated eyes cannot readily be applied to 25 small toys for young children.

I am also aware that various luminescent materials have been applied to the faces of watches, clocks and various other objects in 30 order to make them visible in the dark and I do not therefore claim broadly the application of luminescent material to such commercial articles.

It is well known that many children have 35 a natural aversion for darkness and will not go to sleep unless the parent or some other person remains in the room or within sight of the child or unless a light is left in the room. In many instances however, children 40 are forcibly compelled to go to sleep in a dark room and as a result develop nervous diseases which are retained through a greater or less portion of their lives.

The present invention contemplates the 45 production of a toy, such as a doll or other simulation of a living being, for example, a dog, cat, bear, etc., having luminescent eyes which toy may be taken to bed with the child and which the latter may be assured will 50 watch over it during the night, thereby allaying the fears of darkness.

A further object of the invention is to provide a doll or other object of the character specified having a soft and pliable body 55 which may be handled by the child in the night as well as the day time without danger

of injury to the child and which will be provided with eyes having a luminous appearance.

Other objects and features of the invention will more fully appear from the following description and the accompanying drawings and will be pointed out in the annexed claims.

A preferred embodiment of the invention 65 is disclosed in the accompanying drawings in which

Figure 1 is a conventional illustration of a doll, and,

Fig. 2 is a detail view of a suitable form 70 of eye adapted to be applied to a doll or other toy, and,

Fig. 3 is an enlarged vertical sectional view of a preferred form of eye.

The toy illustrated in the accompanying 75 drawing comprises a doll having a body 1, legs 2, arms 3, and a head 4, having eyes 5 secured to said head by any suitable means.

The eyes may be in the form of disks 80 preferably having a curved outer surface and a flat or curved back surface, one of said surfaces being provided with a layer or coating of luminescent material, said layer or coating being applied either directly to the material forming the eye or to a setting 85 which supports the eye and by means of which it may be attached to the head of the doll or other toy.

As illustrated in the preferred embodiment of the invention disclosed herein the eye 90 comprises a central dark portion 6 corresponding to the pupil of the natural eye, surrounded by a luminous band 7 produced by a layer or coating comprising a luminescent material preferably a radium composition 95 which will retain its luminescent property for a long time, and corresponding to the iris of the eye.

Preferably the eyes are formed of a body portion 8 presenting a convex outer surface 100 which may be coated with a luminescent composition. The eyes preferably are made of transparent material to produce the effect of a lens, the luminescent material being applied to the back surface of said lens.

The eye comprises a hemispherical body portion 8 having a flat back surface supported in a suitable setting such as a disk 9 having a circumferential flange 10 engaging over the edge of the hemispherical body 110 portion 8 of the eye, a layer of luminescent composition 12 being applied either as a

coating to the back side of the body portion of the eye or contained in a setting 9 in the form of a disk or preferably a ring surrounding the central dark spot. The 5 setting may be provided with any suitable means for attaching it to the head of the doll or other device. A convenient means comprises shanks 14, 15 which are secured at one end to the disk 9 and adapted to be 10 inserted through the outer wall of the head and bent laterally into the position illustrated in dotted lines thereby holding the eye in position. It will however, be understood that any suitable means may be provided 15 for securing the eye to the toy. A preferred form of eye is illustrated in Fig. 3 which comprises a body 15 of transparent material having a curved preferably substantially hemispherical surface 16 and a 20 concavely curved rear surface 17 provided with a central cavity 18 presenting a surface of greater concavity than the surface 17, the layer or coating 19 of luminescent material being applied to the surface 17 while 25 a coating or layer of dark material 20 is applied to the central concavity 18.

By such construction the coatings of dark and luminescent material can be readily located and applied so that the eyes will have 30 a uniform appearance. The eye may be mounted in a setting similar to that illustrated in Fig. 2 comprising a disk 21 having a circumferential annular flange 22 and shank 23, 24 for securing the eye to the head 35 of the toy.

In order that the children may not be injured by this toy whether in the form of a doll or other object the body portion and head desirably are formed of a soft flexible 40 material covered with pliable material such as a soft cloth. The other features of the toy may be formed in any suitable manner, as by embroidery, painting, or stenciling.

It will however be understood that my 45 invention is not confined to the use of a luminous eye with a doll or toy of the specific character illustrated but may be employed in dolls having china and composition heads and which are provided either 50 with stationary or movable eyes, and that various modifications in construction and form of the toy may be made within the spirit and scope of the invention, the object of which is broadly to provide a toy having 55 eyes comprising a luminescent material of a suitable character to enable the child to be assured of the presence of an "overseeing eye."

My invention particularly contemplates 60 avoiding the use of any luminous means which comprises a device, the luminosity of

which is dependent upon incandescence since in the latter case the heat of the incandescent would be likely to cause fire and would be wholly unadapted for the purpose specified. 65

Having thus described my invention what I claim as new and desire to secure by Letters Patent is:

1. A toy formed in simulation of a living being and having eyes provided with transparent surfaces and comprising a central dark portion corresponding to the pupil and a surrounding portion corresponding to the iris of the natural eye, comprising luminescent material. 70

2. A toy comprising a body and head of flexible material stuffed with soft pliable material, said head being provided with eyes having transparent surfaces and presenting central dark portions corresponding to the pupil and surrounding portions corresponding to the iris of the natural eye, comprising luminescent material. 80

3. An eye for toys and the like, comprising a transparent front surface and presenting a dark portion corresponding to the pupil and a surrounding portion corresponding to the iris of the natural eye, said surrounding portions comprising luminescent material. 85

4. An eye for toys and the like comprising a transparent body portion presenting a curved front surface simulating the lens of an eye and a back surface, said back surface being provided with a layer of luminescent material. 90

5. An eye for toys and the like comprising a transparent body portion presenting a curved front surface simulating the lens of an eye and a back surface, said back surface being provided with a central dark portion surrounded by an annular layer of luminescent material. 100

6. An eye for toys and the like comprising a transparent body portion presenting a curved front surface and a curved back surface, a setting for said eye having attaching means and a layer of luminescent material intermediate of said back surface and said setting. 105

7. An eye for toys and the like comprising a transparent body portion presenting a convexly curved front surface and a concavely curved back surface having a central depression of greater concavity, a coating of dark material in said central depression and a surrounding annular layer of luminescent material. 115

In testimony whereof I have signed my name to this specification.

FLORENCE GARRIGUE.
